[57] CLAIM

The ornamental design for a device to remove sulfur from water systems, as shown.

DESCRIPTION

FIG. 1 is a top perspective view;
FIG. 2 is a top plan view;
FIG. 3 is a bottom plan view;
FIG. 4 is a rear elevational view;
FIG. 5 is a side elevational view;
FIG. 6 is a front elevational view;
FIG. 7 is a side perspective view shown in a use; and,
FIG. 8 is a perspective view shown in another use.
The hose portion of the claimed design is shown fragmented to indicate indeterminate length.
